(57) **CLAIM**

The ornamental design for a pet coat with detachable liner, as shown and described.

DESCRIPTION

FIG. 1 is a perspective view of a pet coat with a detachable liner inside the pet coat, showing my new design;

FIG. 2 is a bottom plan view thereof, shown in a flat configuration with tabs on the detachable liner shown tucked into tabs on the pet coat;

FIG. 3 is an exploded perspective view of the pet coat with the liner detached;

FIG. 4 is a front elevation view thereof;

FIG. 5 is a rear elevation view thereof;

FIG. 6 is a right-side elevation view thereof;

FIG. 7 is a left-side elevation view thereof;

FIG. 8 is a top plan view thereof;

FIG. 9 is a bottom plan view thereof;

FIG. 10 is a top plan view thereof, shown in a flat configuration; and,

FIG. 11 is a bottom plan view thereof.

The drawings are shaded to indicate different materials. The stippling on the liner represents a material (e.g., fleece or fur) differing from the material of the pet jacket.

The broken lines showing coat hardware (fasteners and clips) depict environmental subject matter only and form no part of the claimed design. The remaining broken lines depict stitching that form no part of the claimed design.
